UNITED STATES PATENT OFFICE.

HENRY STEINES, OF ST. PAUL, MINNESOTA, ASSIGNOR TO THE UNITED STATES
BEDDING CO., OF ST. PAUL, MINNESOTA, A CORPORATION OF MINNESOTA.

WIREWORKING MACHINE.

1,414,053.

Specification of Letters Patent. Patented Apr. 25, 1922.

Application filed April 28, 1919. Serial No. 293,123.

To all whom it may concern:

Be it known that I, HENRY STEINES, a citizen of the United States, residing at St. Paul, in the county of Ramsey and State 5 of Minnesota, have invented certain new and useful Improvements in Wireworking Machines, of which the following is a specification, reference being had to the accompanying drawings.

10 This invention relates to certain improvements in wire working machines and has relation more particularly to a machine of this general character especially designed and adapted for use in connection with twisted 15 wire cables such as are generally employed in connection with bed fabrics or the like, and it is an object of the invention to provide a machine of this type having novel and improved means whereby the twisted 20 cable, after it has been delivered from the weaving machine, is passed between coacting members which operate to exert pressure on such cable to reduce or condense and stretch the same so that the finished 25 cable is improved in ductility and resiliency and is increased in tensile strength in view of the fact that each strand comprised in the cable is caused to closely contact or adhere to the strands in immediate proximity 30 thereto and in such a manner that the tining or covering of the strands becomes substantially homogeneous and continuous.

It is also an object of the invention to provide a machine of this general character 35 including coacting condensing or compression members, together with novel and improved means whereby the cable to be worked is positively fed relative to said members.

The invention consists in the details of 40 construction and in the combination and arrangement of the several parts of my improved wire working machine whereby certain important advantages are attained and the device rendered simpler, less expensive 45 and otherwise more convenient and advantageous for use, as will be hereinafter more fully set forth.

The novel features of my invention will hereinafter be definitely claimed.

50 In order that my invention may be the better understood, I will now proceed to

describe the same with reference to the accompanying drawings, wherein:

Figure 1 is a view in top plan, with a portion broken away, of a wire working 55 machine constructed in accordance with an embodiment of my invention.

Figure 2 is a view in front elevation of the machine as herein embodied, the supporting frame being shown in fragment. 60

Figure 3 is a view partly in side elevation and partly in vertical section of the machine as herein disclosed.

Figure 4 is a fragmentary view partly in elevation and partly in section illustrating 65 certain of the mountings for the disc carrying arbors, and

Figure 5 is a fragmentary view in cross section taken through the upper stretch of the endless apron and the side boards 70 co-acting therewith.

As disclosed in the accompanying drawings, F denotes a frame of desired configuration and which includes the two upstanding columns or standards 1 having their upper end portions bifurcated and with the upper end of each of the kerfs 2 closed by the cap or plate 3. Slidably mounted in each of the kerfs 2 is a pair of bearings 4 and interposed between said bearings 4 is an 75 expansible member 5, herein disclosed as a heavy coil spring, and which expansible member serves to maintain said bearings separated. Threaded through each of the caps or plates 3 is a set screw 6 or the like 80 which engages an upper bearing 4, whereby the relative positions of the bearings 4 in each pair may be regulated with a resultant regulation of the tension of the expansible member 5. 90

The lower bearings 4 rotatably support an arbor or shaft 7 which extends beyond the frame F and suitably fixed to the extended portion of said arbor or shaft is a pulley 8 or the like, whereby said shaft or arbor may be coupled with a suitable source of power. 95

The upper bearings 4 rotatably support the arbor or shaft 9 which also has an end portion extending beyond the frame F and which extended portion has fixed thereto a gear 10 meshing with a gear 11 of equal ra- 100

radius fixed to the arbor or shaft 7 inwardly of the pulley 8. The gears 10 and 11 cause the arbors or shafts 7 and 9 to rotate in unison but in reverse directions.

5 Fixed to the arbors or shafts 7 and 9 at a point between the standards or columns 1 are the discs 12 having their peripheries provided with the circumferentially disposed grooves or channels 14 extending entirely therearound with the groove or channel of one disc registering with the groove or channel of the second disc. The relative positions of the discs 12 may be readily regulated or controlled by the set screws 6 or the like hereinbefore referred to.

10 15 denotes a suitably supported endless apron having its upper stretch *a* traveling toward the discs 12 and substantially in longitudinal alinement with the bight of the discs 12. Coacting with the longitudinal marginal portions of the upper stretch *a* of the apron 15 are the side boards 16 arranged transversely in convergence toward the apron, whereby a trough is provided of 20 which the upper stretch *a* of the apron 15 constitutes a movable bottom.

15 The apron 15 is directed around suitably supported pulleys or drums 17 and the shaft 18 of the pulley or drum adjacent the discs 30 12 extends beyond the side of said apron and has fixed thereto a sprocket wheel 19 in alinement with a second sprocket wheel 20 fixed to the extended portion of the arbor or shaft 7 and preferably between the 35 pulley 8 and the gear 11. Disposed around the sprockets 19 and 20 is the chain 21, whereby the apron 15 is driven or operated from the arbor or shaft 7.

40 The upper stretch *a* of the apron 15 is preferably of a length to sufficiently approach a weaving or twisting machine to receive the work or cable as delivered from said machine so that the apron 15 will operate to positively feed the cable or work toward the discs 12. The work or woven strand or cable automatically finds its way into the substantially circular orifice formed by the registering grooves 14 and the discs 12 and as said work or strand passes between 45 the discs, the pressure on said work or strand results in a condensing and stretching thereof whereby the cable or strand is materially improved in ductility and resiliency and is increased in tensile strength because each 50 and every strand of the cable or work is made to closely contact or adhere to the strands in immediate proximity thereto and in such a manner that the tinning or covering of the strands becomes substantially homogeneous and continuous.

55 It is to be particularly stated that my improved machine is particularly adapted for use in the reduction or condensing of a cable or work composed of loosely woven wire strands delivered from the weaving or twist-

60 ing machine as a hollow or tubular cable of the type used in the making of bed springs or the like. By having the springs 5 normally maintaining the discs 12 separated, the production of the finished work 70 at substantially a desired diameter is assured, and furthermore, should there be any undue obstruction or hindrance offered to the action of the discs 12 as the work passes therebetween, the springs 5 permit sufficient 75 separation of said discs 12 to allow the work to continue therethrough. The springs 5 also act as cushions to keep the pressure of the discs 12 uniform throughout an entire 80 operation. In doing this the grooves or channels 14 in the peripheries of the disks 12 are maintained in constant alignment with the marginal edges of the disks in coincidence at all times, thus correcting the 85 action produced by the varying pressure on the cable going between the discs 12.

85 Were the channels 14 not in strict alignment, the overlapping edge or marginal portion would bite into the cable and render the cable defective.

90 From the foregoing description, it is thought to be obvious that a wire working machine constructed in accordance with my invention is particularly well adapted for use by reason of the convenience and facility with which it may be assembled and operated, and it will also be obvious that my invention is susceptible of some change and modification without departing from the principles and spirit thereof and for this 95 reason I do not wish to be understood as limiting myself to the precise arrangement and formation of the several parts herein shown in carrying out my invention in practice except as hereinafter claimed because 100 it is believed that my invention as herein disclosed is of such character as to permit the reducing or condensing discs to have a plurality of peripheral grooves to permit the work or cables to be operated upon in 105 gang, or that a plurality of sets of condensing or reducing discs may be used to operate upon a cable or cables in sequence.

110 I claim:

115 A machine for condensing and reducing loosely woven wire cables comprising a frame, a pair of upstanding standards integrally formed with said frame, the upper end portions of the standards being bifurcated to provide vertical guideways, a plate 120 secured to the upper end of each of the standards for closing the guideways, a pair of vertically spaced bearing blocks slidably mounted in each of the guideways for movement lengthwise thereof, the blocks of each 125 pair having sliding movement in the guideway one independently of the other, an expandable spring interposed between the blocks of each pair for constantly urging said blocks in a direction one from the other, 130

a member threaded through each of the plates and engaging an upper bearing block for adjusting the relative positions of the bearing blocks of each pair with a resultant regulation of the tension of the coacting expandible spring, substantially parallel arbors supported by the bearing blocks, means for connecting said arbors for rotation in unison but in reverse directions, and coacting discs carried by the arbors and having registering channels disposed entirely around the peripheries thereof. 10

In testimony whereof I hereunto affix my signature in the presence of two witnesses.

HENRY STEINES.

Witnesses:

Jos. I. SILBAN,
CHARLES B. FRALEY.
